Primary Examiner—M. H. Tung*Attorney, Agent, or Firm*—Finnegan, Henderson, Farabow, Garrett & Dunner, L.L.P.[57] **CLAIM**

The ornamental design for an icon for a computer screen, as shown and described.

DESCRIPTION

FIG. 1 is a perspective view of an icon for a computer screen;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of a eighth embodiment thereof;

FIG. 9 is a front view of a ninth embodiment thereof; and,

FIG. 10 is a front view of a tenth embodiment thereof.

The broken line drawing of a computer screen in all views is for illustrative purposes only and forms no part of the claimed design.
